(57) **CLAIM**

The ornamental design for an elastic loop, as shown and described.

DESCRIPTION

FIG. 1 is a perspective view of the first embodiment of an elastic loop, showing our new design;

FIG. 2 is a left side view thereof;

FIG. 3 is a top view thereof;

FIG. 4 is a left end view thereof;

FIG. 5 is a right end view thereof;

FIG. 6 is a right side view thereof;

FIG. 7 is a bottom thereof;

FIG. 8 is a perspective view of the second embodiment of an elastic loop;

FIG. 9 is a left side view thereof;

FIG. 10 is a top view thereof;

FIG. 11 is a left end view thereof;

FIG. 12 is a right end view thereof;

FIG. 13 is a right side view thereof; and,

FIG. 14 is a bottom thereof.

The evenly spaced broken lines are for the purpose of illustrating environment and form no part of the claimed design. The dot-dash-dot broken-away heavy weight lines in FIGS. 8, 10 and 14 themselves form no part of the claimed invention, and are provided to indicate that any portion of the article beyond what is shown forms no part of the claimed design. The short-long-short dash lines shown in the drawings are cut lines.
